No. 13,416

Nov 14, 1882

UNITED STATES PATENT OFFICE.

JOHN L. POPE, OF CLEVELAND, OHIO.

DESIGN FOR A CARRIAGE-STEP.

SPECIFICATION forming part of Design No. 13,416, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and original Design for Carriage-Steps, of which the following is a specification, reference being had to the accompanying photographic illustration, forming part thereof.

My invention relates to a new design for carriage-steps; and it consists in providing the upper surface of the step with ribbed work in the form of semicircles and ellipses and thereby producing a handsome and striking appearance.

In the accompanying photograph, $a a' a' a'$ are four semicircular ribs, which run from near either corner of the step, and, crossing each other at about the center of the latter, terminate at the opposite corner. These four semicircular or arch-like ribs, laid out as they are, form four elliptically-shaped figures, $a a' a a'$, &c., inclining toward the center of plate from the corners of the latter. Formed of raised work, integral with the arch-like ribs and disposed in an opposite direction from the elliptical-shaped figures $a a' a a'$, &c., made there-

by, are four more figures elliptical in outline, which I have designated by the letters $b b b b$, and which, as will be seen, run diagonally of the plate. The general effect of the ornamentation is the appearance to the eye of two crossed ellipses at each corner of the plate and one large ribbed ring running all around the plate and touching at four points, c , of the inner edges of the sides thereof.

The angles formed by the various described figures and now shown in the form of open-work may be closed up in the casting of the plate, and yet the raised work of the ornamentation still produce my novel design.

What I claim as new, and desire to secure by Letters Patent, is—

The design for a carriage-step, consisting of raised semicircular and elliptical-shaped figures, disposed substantially as shown.

—In testimony whereof I have hereunto set my hand this 31st day of May, 1882.

JOHN L. POPE.

In presence of—

A. A. POPE,
C. M. COPP.
